UNITED STATES PATENT OFFICE

WINFIELD R. DUNKIN, OF HUNTINGTON, INDIANA

IRONING BOARD MOUNTING

Application filed February 5, 1932. Serial No. 591,209.

The invention relates to an ironing board mounting and more especially to a transfer mounting for ironing boards in cupboards, bookcases, cabinets or the like.

5 The primary object of the invention is the provision of a mounting of this character wherein an ironing board can be conveniently stored within an enclosure and when it is desired to make use of the enclosure for the 10 storing of articles therein, the ironing board when placed therein can be transferred from its support within the enclosure onto the door so that when the door is open free access may 15 be had to the shelves or other hangers or supports interiorly of the enclosure.

Another object of the invention is the provision of a mounting of this character wherein in the ironing board when within the enclosure can be swung to usable position and when 20 not in use is concealed within the enclosure, although such enclosure will be freely accessible without the ironing board when therein constituting a barrier to its shelves, supports 25 or hangers, as the ironing board can be transferred from its supported position in the enclosure onto the door to be carried thereby and thus avoiding any blocking of the access 30 to the shelves, supports or hangers of the enclosure when it is desired to have free access thereto.

A further object of the invention is the provision of a mounting of this character wherein in the construction thereof is novel in form and the same can be readily manipulated from 35 without the enclosure, the ironing board being normally concealed within the enclosure in confronting relation to the shelves, supports or hangers therein and can be readily shiftable or transferred onto the door for the enclosure for free accessibility to the enclosure or vice versa for the use of the ironing board.

A still further object of the invention is the provision of a mounting of this character which is comparatively simple in construction, thoroughly reliable and efficient in its 45 purpose, neat and attractive in appearance, strong, durable, readily and easily operated, and inexpensive to manufacture.

With these and other objects in view, the 50 invention consists in the features of construc-

tion, combination and arrangement of parts as will be hereinafter more fully described in detail, illustrated in the accompanying drawings, which disclose the preferred embodiment of the invention, and pointed out in the claims hereunto appended.

In the accompanying drawings:

Figure 1 is a front elevation of an enclosure such as a cupboard showing the door thereof in open position, the ironing board therein and the mounting constructed in accordance with the invention applied.

Figure 2 is a view similar to Figure 1 showing a changed position of the ironing board, namely, carried upon the door to the enclosure.

Figure 3 is an enlarged vertical longitudinal sectional view on the line 3—3 of Figure 2 looking in the direction of the arrows.

Figure 4 is a horizontal sectional view showing the door closed.

Figure 5 is a fragmentary detail elevation showing the hinge mounting of the ironing board when within the enclosure.

Figure 6 is a sectional view on the line 6—6 of Figure 5 looking in the direction of the arrows.

Figure 7 is a view similar to Figure 6 showing the ironing board in a shifted or lowered position from normal vertical position.

Figure 8 is a view similar to Figure 5 showing the board elevated for the transfer thereof from the enclosure onto the door.

Figure 9 is a perspective view of one of the bearings for the ironing board.

Figure 10 is a fragmentary vertical sectional view through one of the shelves of the enclosure showing in elevation a snap keeper.

Figure 11 is a sectional view on the line 11—11 of Figure 10.

Figure 12 is a perspective view of the keeper engaging plate.

Figure 13 is a perspective view of the hinge shown in Figure 5 and detached from the board.

Figure 14 is a perspective view of an adjunct thereof.

Figure 15 is a detail perspective view of the transfer means.

Figure 16 is a fragmentary sectional view on the line 16-16 of Figure 2.

Figure 17 is a perspective view of the centering members as shown in Figure 16.

5 Similar reference characters indicate corresponding parts throughout the several views in the drawings.

Referring to the drawings in detail, A designates generally a cupboard or built-in 10 wall cabinet of any standard construction and B the swinging door thereto, while within this cabinet is a series of shelves 10, these being cut away at their front edges as at 11 to provide a clearance for the ironing board 12 which is adapted to be concealed within the 15 cabinet A when not in use and is transferable from the cabinet A to the door B by the mounting constituting the present invention and hereinafter fully described.

20 Suitably fixed in the lower portion of the cabinet A at opposite sides thereof are bearings 13 providing open hangers 14, while disposed across the lowermost edge of the ironing board 12 is a pintle 15, the same being 25 held in pintle sleeves 16 of strap brackets 17, the ends of said pintle 15 being extended laterally beyond opposite longer edges of the ironing board 12 to removably fit within the hangers 14 and in this fashion the said ironing board 12 is swingingly supported within the enclosure or cabinet A for vertical movement whereby it may be pulled outwardly to a horizontal position as shown by dotted lines in Figure 3 from its normal vertical 30 or perpendicular position as shown by full lines in said figure of the drawings. The board 12 when in the horizontal usable position is supported by a foldable prop or leg 18 which folds against the board 12 when in 35 40 perpendicular or upright position.

Carried by one of the uppermost shelves 10 within the cabinet A at opposite ends of the cutaway portion 11 of said shelf are spring pressed snap keepers 19, each adapted 45 for snapping engagement in a slot 20 in an engaging plate 21 mounted on the ironing board at each of its longer side edges and in this fashion the said board 12 is retained in perpendicular or vertical position when 50 hung in the cabinet A as shown in Figure 1 of the drawings and thus the accidental swinging of the board 12 is prevented.

Carried by the lower portion of the door B is a transferring mechanism which 55 comprises a stud shaft 22 journaled transversely of the door B in plates 23 and 24 respectively, the latter being carried at the inner side of the door and the plate 23 at the outer side thereof. The plate 24 is formed with a bail 60 25 and adapted to swing in this bail is a rotatable lifter 26, the same being fixed to the shaft 22 and such lifter is designed, when the door is closed, to engage with the pintle 15 and on rotation of such lifter to raise the board 12 so as to lift the pintle from the

hangers 14 of the bearings 13 whereby such board 12 can be transferred from the cabinet A onto the door B, the latter at its upper portion being provided with a bail 27 into which is introduced the upper end of the 70 board 12 when being transferred by the lifter 26 and such lifter is formed with a seat 28 for the lower end of the board 12 and in this fashion carried upon the door B.

The shaft 22 has its outer end extended 75 through an escutcheon plate 29 mounted on the outer plate 23 and carries at this outer end a crank handle 30 so that said lifter 26 can be turned for the raising and lowering of the board when the door B has been closed 80 to the cabinet A. Thus it will be seen that the board 12 may be transferred from the door B at its inner face into the cabinet A to engage in the hangers 14 or discharged from the hangers 14 and transferred onto the door 85 at its inner side by the transfer mechanism hereinbefore described.

The plate 24 has mounted thereon a stationary stop 31 which limits the swinging of the lifter 26 in one direction and also a swinging stop 32 which when in one position latches and lifter 26 against movement and in another position permits the turning of the lifter in one direction. This swinging stop 32 is manually manipulated when the door 90 is opened and when in the path of the lifter 26 holds the same immovable to retain the board 12 carried upon the door B at its inner side.

95 The underside of the board 12 carries a female member 33 of a centering device, while the door at its inner face carries the male member 34 of such device so that when the door B is closed these members 33 and 34 interfit with each other to properly center the 100 board with respect to the cutaway portions of the shelves 10 and with relation to the hangers 14 for the positive and sure engagement of the pintle 15 with said hangers 14 or the disengagement thereof.

105 The strap brackets 17 each constituting a hinge part has overlying the same a retaining plate 35 having a retaining or keeper lip 36 to cooperate with the hanger 14 so as to prevent the pintle end disengaging from the hanger 14 when the board is within the cabinet A and being swung from vertical to horizontal position or vice versa. This lip 36 of the retaining plate 35 also vertically guides the pintle end into and from the hangers 14 110 when the ironing board 12 is lowered or raised by the transfer mechanism hereinbefore described.

115 It should be clearly apparent that the ironing board 12 may be transferred from the door B into the cabinet and hung therein as shown in Figure 1 of the drawings, the cabinet being identified by A or onto the door as shown in Figure 2 of the drawings. The ironing board 12 when hung within the cabi- 120 125 130

net may be lowered from perpendicular position to horizontal using position as shown by dotted lines in Figure 3 of the drawings and in this horizontal position will be supported by the prop or leg 18 during use thereof.

What is claimed is:—

1. In a mounting of the character described, a cabinet having a door, means within the cabinet and upon the door for the hanging of an ironing board, and means carried by the door for transferring the board from the hanger within the cabinet to the hanger on the door or vice versa.
2. In a mounting of the character described, a cabinet having a door, means within the cabinet and upon the door for the hanging of an ironing board, means carried by the door for transferring the board from the hanger within the cabinet to the hanger on the door or vice versa, and means for enabling the swinging of the ironing board when within the cabinet to horizontal using position.
3. In a mounting of the character described, a cabinet having a door, means within the cabinet and upon the door for the hanging of an ironing board, means carried by the door for transferring the board from the hanger within the cabinet to the hanger on the door or vice versa, means for enabling the swinging of the ironing board when within the cabinet to horizontal using position, and means for latching the ironing board in normal perpendicular position within the cabinet.
4. In a mounting of the character described, a cabinet having a door, means within the cabinet and upon the door for the hanging of an ironing board, means carried by the door for transferring the board from the hanger within the cabinet to the hanger on the door or vice versa, means for enabling the swinging of the ironing board when within the cabinet to horizontal using position, means for latching the ironing board in normal perpendicular position within the cabinet, and means on the board and door for the centering of the ironing board when being transferred.
5. In a mounting of the character described, a cabinet having a door, means within the cabinet and upon the door for the hanging of an ironing board, means carried by the door for transferring the board from the hanger within the cabinet to the hanger on the door or vice versa, means for enabling the swinging of the ironing board when within the cabinet to horizontal using position, means for latching the ironing board in normal perpendicular position within the cabinet, means on the board and door for the centering of the ironing board when being transferred, and means for manual operation of the transfer means exteriorly of the door.
6. In a mounting of the character de-

scribed, a cabinet having a door, means within the cabinet and upon the door for the hanging of an ironing board, means carried by the door for transferring the board from the hanger within the cabinet to the hanger on the door or vice versa, means for enabling the swinging of the ironing board when within the cabinet to horizontal using position, means for latching the ironing board in normal perpendicular position within the cabinet, means on the board and door for the centering of the ironing board when being transferred, means for manual operation of the transfer means exteriorly of the door, and means for latching the transfer means when in one position.

In testimony whereof I affix my signature.

WINFIELD R. DUNKIN.
